PRODUCTION OF AVIATION GASOLINE

James A. Anderson, Jr., Goose Creek, Tex., assignor to Standard Oil Development Company, a corporation of Delaware

Application July 21, 1944, Serial No. 545,976

4 Claims. (Cl. 196—52)

The present invention relates to a process for producing aviation fuel from catalytically cracked naphtha. More particularly it is concerned with a process for recovering iso-paraffins from catalytically cracked naphtha substantially free from aromatics and olefins. In its more specific aspects the present invention contemplates the solvent extraction of a selected catalytically cracked naphtha fraction and the recovery of a fraction from the solvent raffinate comprising substantially the iso-paraffins.

During the last few years catalytic cracking has reached the stage of development where it has become an important tool of the petroleum refiner in producing aviation gasoline. While the catalytically cracked naphtha is suitable for the production of aviation gasoline, its use is open to some objection in that drastic chemical treatment is necessary before the fuel is suitable for use in the aviation motor. For example, it is often necessary to treat the catalytically cracked naphtha with a large amount of sulfuric acid to destroy the olefins or to hydrogenate the whole fraction to make it suitable for aviation fuel. When acid treatment is contemplated, it is often necessary to supplement the acid treatment with inhibition to provide stability for the fraction.

In accordance with the present invention it is unnecessary to resort to the aforementioned processes in producing aviation fuel components from catalytically cracked naphtha. In my invention, I extract a fraction boiling up to about 250° F. with a solvent which will separate paraffinic constituents from the alicyclic, olefinic and aromatic constituents to obtain a fraction comprising essentially the iso-paraffins. In the solvent extraction the alicyclic, olefinic and aromatic hydrocarbons are largely concentrated in the extract and may then be recovered therefrom by a treating operation which may involve a second extraction with a solvent, distillation and hydrogenation, as may be desired. My invention allows the obtaining, from a catalytically cracked fraction, of desirable aviation fuel components without treatment of the total fraction.

In the catalytic cracking of a gas oil for example, there is produced a large quantity of iso-paraffins, olefins, naphthenes and aromatics with very little of the n-paraffins resulting. By selecting a fraction boiling up to about 250° F., it is possible to solvent extract such a fraction and obtain a raffinate fraction comprising essentially the iso-paraffins. By virtue of my discovery that this fraction contains substantially no n-paraffins and by virtue of the fact that it contains very

little aromatics, it is possible to recover the iso-paraffins by a very inexpensive process as compared to the more expensive processes as practiced in the art.

5 The present invention will be better understood by reference to the accompanying single figure which is a flow plan illustrating a preferred embodiment.

Referring now to the drawing, numeral 11 designates a feed line through which a gas oil boiling in the range of about 450° to 800° F. is introduced into catalytic cracking zone 12. Catalytic cracking zone 12 may be any type of catalytic cracking operation but for purposes of illustration, it will be assumed that it embodies a cracking operation of the so-called "fluid catalyst" type. In catalytic cracking zone 12, the gas oil is subjected to cracking conditions employing temperatures between 800° and 1100° F. and pressures up to about 15 50 pounds per square inch. Preferably, pressures of the order of 15 pounds per square inch are employed. A silica-alumina catalyst either of natural or synthetic origin may be employed satisfactorily.

20 25 The catalytic cracking zone 12 may be operated on either a naphthenic type of gas oil or a paraffinic type of gas oil. It has been observed that when employing either naphthenic or paraffinic gas oils at low conversion and high throughputs formation of iso-paraffins is favored; irrespective, however, of the operation of the catalytic cracking zone 12, it is possible to practice my invention and obtain a satisfactorily pure iso-paraffin fraction. The conditions obtaining in 30 35 catalytic cracking zone 12 are known in the art and do not form part of this invention but are given in some detail to allow proper understanding thereof.

30 35 There is discharged from catalytic cracking zone 12 through line 13 the catalytically cracked product which is introduced thereby into distillation zone 14. It is, of course, well understood that the distillation zone 14 may comprise a number of distillation towers each provided with heating means 15, but for ease of description in the present invention, reference will be made to a single tower. Distillation zone 14 is provided with a line 16 for discharge of heavier constituents, line 17 for removal of components boiling above 250° F., line 18 for recovery of a fraction boiling between about 105° and 250° F., and line 19 for discharge of products boiling below about 105° F. which may be further processed for recovery of valuable vaporous constituents. The desired 45 50 cracking fraction, boiling at temperatures in the

range between about 105° and 250° F. is discharged from fractionating zone 14 by line 18 and is introduced into an extraction zone 22. Extraction zone 22 may be either an extractive distillation zone, employing countercurrent contact between a vaporous hydrocarbon feed and a liquid selective solvent, or a conventional liquid phase solvent extraction zone, employing countercurrent contact between a liquid hydrocarbon feed and a liquid selective solvent. It will be understood, of course, by those skilled in the solvent extraction art that, when extractive distillation is employed in zone 22, it may be desirable to process a fraction having a narrower boiling range than is described above. For purposes of illustration, however, it will be assumed that extraction zone 22 is of the conventional liquid-liquid phase type, the extraction is carried out on a fraction having the boiling range specified above, and the solvent is introduced into zone 22 through lines 20 and 21.

The type of solvent employed in extraction zone 22 is selected from the class of compounds illustrated by phenol, furfural, diethylene glycol, triethylene glycol and the polyethylene glycols and mixtures thereof. For purposes of illustration only it may be assumed that a mixture of polyethylene glycols and ethylene glycol is employed in extraction zone 22 as the selective solvent. For best results in the process to obtain a raffinate comprising essentially iso-paraffins a solvent to hydrocarbon ratio in the range between 5:1 and 15:1 is desirable. The temperature obtaining in solvent extraction zone 22 may be varied considerably, but a temperature of the order of about 150° F. at atmospheric pressure is usually desirable. To obtain the iso-paraffin substantially free from the alicyclic, olefinic and aromatic hydrocarbons, solvent extraction zone 22 should include 30 to 50 stages in which the conditions are adjusted to obtain raffinate and extract phases which are withdrawn therefrom by lines 23 and 24, respectively.

The raffinate phase, containing a small amount of solvent is discharged by way of line 23 into the solvent stripper 25 which is provided with a heating means 26. The solvent is taken off from solvent stripper 25 by line 21 and the iso-paraffins are discharged from stripper 25 by line 27 and are then suitable for use as an aviation fuel constituent or may be employed as a feed stock for an alkylation process as desired. It is to be understood by the skilled worker that, depending on the boiling point of the solvent employed, in some instances instead of the iso-paraffin being taken overhead and the solvent withdrawn as bottoms from tower 25 in the manner illustrated, the solvent may be distilled overhead and the iso-paraffins withdrawn as bottoms by way of line 21.

The extract phase is introduced by line 24 into a second solvent stripper 28 which is similar to stripper 25, and is equipped with a heating means 29. Solvent is recovered from stripper 28 by line 20 and returned to extraction zone 22 while the hydrocarbon constituents of the extract are discharged through line 30 and are introduced thereby into a second extraction zone 31. In some instances it may be desirable to discharge the extract hydrocarbons from the system without processing them through extraction zone 31. In this particular instance, valve 32 in branch line 33 would be opened and valve 34 in line 30 would be closed off.

For purposes of illustration, however, it is as-

sumed that it is desired to process the extracted hydrocarbons through the extraction zone 31. A solvent similar to that employed in extraction zone 22 is introduced through line 35 and conditions are adjusted to obtain raffinate and extract phases. In extraction zone 31, it will be desirable to employ a solvent to hydrocarbon ratio in the range between about 4:1 and 12:1, temperatures of the order of about 150° F., with atmospheric pressures, and utilizing between about 15 to 25 stages. The solvent may be selected from the type of solvents employed in extraction zone 22 with the understanding that adjustments may be made for the composition of the hydrocarbons in the extract discharged to zone 31.

The raffinate phase is withdrawn from extraction zone 31 through line 36 and introduced thereby into a third solvent stripper 37 in which temperature and pressure conditions are adjusted by heating means 38. Solvent is withdrawn from stripper 37 by line 39 for reuse in the process while a hydrocarbon component comprising essentially olefinic and alicyclic constituents is discharged from stripper 37 by line 40. These hydrocarbons may be discharged from the system by opening valve 41 but preferably are routed to hydrogenation zone 42 through line 43 controlled by valve 44. It is understood, of course, that valve 41 is closed off when the alicyclic and olefinic constituents are routed to zone 42.

The conditions prevailing in hydrogenation zone 42 have been well established in the patent art and are adjusted to obtain a substantially saturated material which may be discharged from zone 42 through line 45, hydrogen for the saturation of the hydrocarbons in zone 42 being introduced through line 46. The effluent discharged from zone 42 by line 45 may be employed as an aviation fuel as is, or it may be blended with the isoparaffins recovered by line 27 or blended with other well known blending agents such as isopentane and tetraethyl lead.

The extract phase discharged from extraction zone 31 by line 47 is introduced thereby into a fourth solvent stripper 48 equipped with heating means 49 and provided with lines 50 and 51. Solvent is withdrawn from stripper 48 through line 50 while aromatics are recovered by way of line 51. It will be understood, of course, that the amount of aromatics recovered will necessarily be small by virtue of the boiling range of the fraction recovered by line 48. The only aromatics that will be included with the stream from line 51 will be benzene or toluene which are also valuable constituents of aviation fuel and may be used as such, as solvents, or as may be desired.

The blending of the streams or portions of the streams from lines 27, 45 and 51 to produce an aviation fuel may be accomplished by line 52, branch line 53 containing valve 54, branch line 55 containing valve 56, and branch line 57 containing valve 58. When it is desired to blend isoparaffins from line 27, saturated hydrocarbons from line 45 and aromatics from line 51, valves 58, 56 and 54 may be opened to allow the isoparaffins, saturated hydrocarbons and aromatics to flow into line 52, where they admix to produce a finished aviation grade fuel.

In a typical operation in accordance with the present invention, a fraction having a boiling range between 105° and 210° F. may be obtained from the fractionating zone 14 of a fluid catalyst cracking operation. This fraction comprises hy-

drocarbons in accordance with the following composition:

Table I

	Per cent
Saturates	50.0
Olefins	47.0
Aromatics	3.0
	100.0

This fraction is then extracted with a solvent under conditions to form raffinate and extract phases. The unsaturated and alicyclic components are concentrated largely in the extract phase and the saturated components concentrated in the raffinate stage. The hydrocarbons contained in the raffinate are largely saturated materials having a composition in accordance with the analysis shown in Table II.

Table II

	Percent
Saturates	91.7
Olefins	6.9
Aromatics	1.4
	100.0

A fraction of the above composition is blended with 4 cc. of tetraethyl lead per gallon and tested for octane number and it is found that the octane number of the leaded fraction is 94.7. Since the equivalent octane number of the aromatics is known to be about 95 and since that of the corresponding olefins is known to be considerably lower, the high octane number of the raffinate fraction demonstrates that it is largely isoparaffinic in nature. By milding treating the raffinate having the composition shown in Table II with sulfuric acid, it is possible to obtain a fraction comprising essentially the isoparaffins.

The extract resulting from the above described operation is freed of solvent and consists largely of olefinic components and alicyclic hydrocarbons. These materials on hydrogenation produce excellent aviation fuel components.

From the above typical operations in accordance with my invention, it will be obvious to the skilled worker that a substantial contribution to the art of producing aviation fuels has been made. Not only has it been shown that it is unnecessary to treat the catalytically cracked naphtha of a suitable boiling range drastically and thereby destroy valuable constituents but it has also been shown that it is possible to recover substantially all components of the catalytically cracked naphtha and to make them available for use in aviation fuel.

The invention is susceptible to considerable variation in the operation of the several steps making up my process. For example the conditions obtaining in extraction zones 22 and 34 may be varied widely depending on the type of solvent being employed therein and the boiling range of the fractions being extracted.

In a similar manner the treatment of the isoparaffin concentrate recovered by line 27 may also be varied. When the isoparaffin concentrate forms a feed to an alkylation system it will be unnecessary to remove the residual olefins contained therein. On the other hand, when the isoparaffin is employed as a blending agent, it may be desirable to treat out the residual olefins by subjecting the fraction to the action of a treating agent such as sulfuric acid or any other olefin reacting materials.

The present invention is not applicable to all types of craking operations. For example, the conventional thermal cracking operation produces products which are unsuitable as charge stocks for my process. It is reiterated that it is only the catalytic cracking operation which produces a suitable feed to be processed as described. And it is only the selected fractions of the catalytically cracked products that can be treated in accordance with my invention to recover the isoparaffins. Specifically, my invention is based on the discovery that the fractions contained in catalytically cracked naphtha boiling below about 250° F. comprises essentially isoparaffins, olefins, alicyclics with very little normal paraffins and aromatics. This discovery is of considerable importance since it is possible to recover substantially all the isoparaffins from the hydrocarbons with which they are usually associated. If a fraction having a corresponding boiling range from a thermal cracking operation is treated in accordance with the steps of the process, a much inferior product containing normal paraffins as well as isoparaffins is obtained.

One great advantage of operating in accordance with the present invention is the chemical stability of the product obtained therefrom. For example, in the conventional treating processes to produce aviation fuel from catalytically cracked naphtha, the products frequently deteriorate in storage unless the treatment given the products is sufficiently severe to destroy valuable constituents contained therein and unless the treatment is supplemented by use of oxidation inhibiting agents. In my process all of these disadvantages are overcome. The isoparaffin concentrate, comprising predominately the saturated hydrocarbons is quite stable in storage. The small amount of olefin components may be removed by a mild chemical treatment. On the other hand the hydrocarbons concentrated in the extract phase may be subjected to hydrogenation treatment which forms a stable product. In the prior processes in which hydrogenation was employed to form a stable product by hydrogenation of the total fraction some 50% of the fraction was submitted unnecessarily to the hydrogenation treatment.

The nature and objects of the present invention having been described and illustrated, what I wish to claim as new and useful and secure by Letters Patent is:

1. A method for producing an olefin-free aviation grade fuel comprising the steps of subjecting a catalytically cracked naphtha to distillation to separate a fraction boiling between 105° and 250° F., solvent extracting said fraction to form a first raffinate fraction and a first extract fraction, separating said first raffinate fraction from said first extract fraction, subjecting said first extract fraction to a second extraction step to separate a second raffinate fraction and a second extract fraction, subjecting said second raffinate fraction to a step of catalytic hydrogenation capable of converting olefins therein to saturated hydrocarbons, removing product from the hydrogenation step and blending it with at least portions of the first raffinate fraction and the second extract fraction to produce an aviation grade fuel.
2. A method for obtaining an aviation grade motor fuel comprising the steps of subjecting a petroleum fraction boiling in the range of 450° to 800° F. to catalytic cracking in a cracking zone containing a catalyst and maintained at a tem-

perature between 800° and 1100° F., removing cracked product from the catalytic cracking zone, distilling said cracked product to separate a fraction boiling in the range of 105° to 250° F., subjecting said fraction to a first solvent extraction step to form a first raffinate comprising a major portion of isoparaffins and a first extract, separately removing the first raffinate and first extract from the first extraction zone, passing the first extract to a second extraction zone and separating it into a second raffinate comprising a major portion of unsaturated hydrocarbons and a second extract comprising a major portion of aromatic hydrocarbons, separately removing the second extract and second raffinate from the second extraction zone, subjecting the hydrocarbons in the second raffinate to hydrogenation conditions capable of saturating substantially all of the unsaturated hydrocarbon therein, and blending at least a portion of the hydrocarbon components from the first raffinate, the second hydrogenated raffinate and the second extract to produce a blended aviation grade fuel.

3. A method for producing an olefin-free aviation grade fuel comprising the steps of fractionally distilling a catalytically cracked naphtha to separate a fraction boiling between 105° and 250° F., solvent extracting said fraction to form a first raffinate fraction and a first extract fraction, separating said first raffinate fraction from said first extract fraction, subjecting the first extract fraction to a second extraction step to separate a second raffinate fraction and a second extract fraction, subjecting said second raffinate frac-

tion to a step of catalytic hydrogenation capable of converting olefins therein to saturated hydrocarbons, removing product from the hydrogenation step and blending it with at least a portion of the first raffinate fraction to produce an aviation grade fuel.

4. A method for obtaining an aviation grade motor fuel comprising the steps of subjecting a petroleum fraction boiling in the range of 450° to 800° F. to catalytic cracking in a cracking zone containing a catalyst and maintained at a temperature in the range of 800° to 1100° F., removing cracked product from the catalytic cracking zone, fractionally distilling the cracked product to separate a fraction boiling in the range of 105° to 250° F., subjecting said fraction to a first solvent extraction step in a first extraction zone to form a first raffinate comprising a major portion of isoparaffins and a first extract, separately removing the first raffinate and first extract from the first extraction zone, passing the first extract to a second extraction zone and there separating it into a second raffinate comprising a major portion of unsaturated hydrocarbons and a second extract comprising a major portion of aromatic hydrocarbons, removing the second raffinate from the second extraction zone, subjecting the second raffinate to hydrogenation conditions capable of saturating substantially all of the unsaturated hydrocarbons therein and blending at least a portion of the hydrocarbon components from the first raffinate and the second hydrogenated raffinate to produce an aviation grade fuel.

JAMES A. ANDERSON, JR.
